UNITED STATES PATENT OFFICE.

SIEGFRIED MARCUS, OF VIENNA, AUSTRIA-HUNGARY.

GAS-ENGINE.

SPECIFICATION forming part of Letters Patent No. 286,030, dated October 2, 1883.

Application filed June 12, 1882. (No model.) Patented in Belgium May 13, 1882, No. 57,900; in France May 15, 1882, No. 148,651; in England May 23, 1882, No. 2,423, and in Italy June 30, 1882, XVI, 14,200, XXVIII, 401, and XVII, 15,462, XXX, 465.

To all whom it may concern:

Be it known that I, SIEGFRIED MARCUS, a subject of the Emperor of Austria, residing at the city of Vienna, in the Austro-Hungarian Empire, have invented certain new and useful Improvements in Gas-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain improvements in the construction of gas-engines; and it has for its object, first, to so construct the piston-cylinder of the engine as to adapt it for use as an air-compressing pump; second, to provide means whereby the liquid employed to produce the explosive gas is thoroughly atomized or vaporized, and which means are of simple construction and operation, and whereby highly volatile and explosive liquids may be 25 employed and the air-compressor dispensed with; third, to provide a means for automatically igniting and exploding the explosive gas by an electric spark produced from a current generated by an electro-magnetic generator, 30 thereby dispensing with the usual batteries, and which is effective in a dry as well as a damp atmosphere, and entirely independent of all slide-valve mechanism; fourth, to effect the ignition and explosion of the gas within 35 the exploding-chamber of the cylinder by an electric spark produced by the current generated by the electro-magnetic apparatus, thereby dispensing with the auxiliary flame or the Ruhmkorff apparatus for producing the spark 40 itself, and avoiding all danger of premature explosion or fire; fifth, to simplify the construction of the entire engine, and to so connect the various parts by simple mechanical appliances as to produce an automatic-timed 45 and regular co-operation of said parts, so that but little care and attendance will be necessary and but little power required when compared with other engines of this class; and, last, to adapt the engine to be worked in any 50 position and used either as a stationary or locomotive engine, its weight being compara-

tively small, and the engine, taking up but a limited space, is in fact adapted for general use.

The invention consists, first, in the method 55 of vaporizing or atomizing the liquid from which the explosive gases are produced by the admixture with such atomized liquid of a certain volume of atmospheric air; secondly, in the means employed for carrying out the above method; thirdly, in the combination, with the engine, of a magneto-electric generator for generating the necessary electricity from which a spark is produced to ignite and explode the explosive gases, and in the means 65 employed for effecting the same; fourthly, in the construction and arrangement of the operating mechanism of the engine, all as herein-after described, and as shown in the accompanying drawings, in which—

70 Figure 1 is a front elevation, Fig. 2 is a side elevation, partly in section, and Fig. 3 is a plan view, of a gas-engine with a vertical piston-cylinder constructed according to my invention. Fig. 4 is an end elevation, and Fig. 75 5 is a side elevation, partly in section, of such an engine with a horizontal cylinder. Fig. 6 is a detail view of the mechanism that operates the admission and exhaust valves. Figs. 7 and 8 show, respectively, a longitudinal and 80 a transverse section of my improved atomizer; and Figs. 9 and 10 are like views of a modification in the construction of the same. Figs. 11, 12, and 13 show, in elevation, in vertical longitudinal section, and by an end view, a magneto-electric generator; and Fig. 14 shows its 85 application to the engine for igniting and exploding the gases.

Like letters of reference indicate like parts wherever such may occur in the above figures 90 of drawings.

I would here remark that the engines heretofore employed, in which is used a hydrocarbon-buret mixed with atmospheric air to produce the explosive gas, and of which the Brayton and Sterne engines are types, have a separate air-pump, which makes such machines very complicated; and one of the objects of this invention is to dispense with this separate air-pump by utilizing the piston-cylinder itself 95 as an air-pump, as will be presently described.

100 Referring to Figs. 1, 2, and 3 of the draw-

ings, F indicates the main frame, of any suitable form and material, to support the mechanism that constitutes the engine.

C is the piston-cylinder, mounted vertically on the frame, and constructed, as usual in this class of machines, with a water-jacket, J, through which a constant circulation of cool water is established, for well-known and obvious purposes. The cylinder C is divided into two chambers, c c', by the piston P. The chamber c here serves as an air-compressing chamber, and the piston P is employed for compressing the air therein at each upward stroke and sucking fresh air at each downward stroke. This chamber c is in communication with a compressed-air reservoir, R, by means of the pipe r and the passages c c', formed in the upper head, C', of the cylinder. In the latter is formed a second passage, c', through which air is admitted to chamber c, which air, after being compressed, escapes into the reservoir R through passages c c'. In the passage c' is located a suction-valve, V, the rod v of which projects some distance above the head of the cylinder and through a stationary guide-arm, g, below which the valve-rod carries a nut or stop, n, that abuts on the under side of said arm, when the valve V has reached its seat. At its upper end the valve-rod carries a thumb-nut, n', and between the latter and the guide g a coil-spring, s, the tension of which tends to hold the valve to its seat in the head of the cylinder. By means of the thumb-nut n' the valve is made adjustable, so as to more or less open the air-inlet port by more or less compressing the spring s, and thereby increasing or decreasing its tension and power exerted upon the valve and rod, as will be readily understood. In the passage c' is located an escape-valve, V', the valve-rod v' of which carries a coiled spring, s', the tension of which tends to hold the valve down to its seat until moved by the pressure of the air within the cylinder-chamber c. The chamber c' of the cylinder C is in communication with the vaporizing or atomizing appliances through passage c', and with the outer atmosphere through passage c' and pipe p'. Each passage is provided with a stop-cock or valve—namely, the passage c' with an admission-valve, s', and the channel c' with an exhaust, s', or other equivalent appliances—whereby the communication between the cylinder-chamber c' may be established with and shut off from the atomizer and outer atmosphere. A portion of the compressed air passes from the reservoir R to the atomizer by pipes r' r'', where such air combines and is saturated with the fine spray or vapor of the liquid used to produce the explosive gas, and carried along with the air to a chamber, c', provided with a perforated diaphragm, d', where the current meets with a second current of air direct from the reservoir and pipe r', and both currents pass from said chamber to the cylinder-chamber c' through passage c''. The pipes r' and r'' are provided with stop-cocks s' s'', respectively,

to regulate the volume of air admitted to the atomizer and chamber c'.

S is the main crank-shaft that carries the two fly-wheels W, and with the cranks S' of said shaft is connected one end of the connecting-rods R' R', the other end being connected with the cross-head H, with which the piston-rod P' is connected, said cross-head traveling, as usual, in a suitable guide-frame, F'. Upon the crank-shaft S are mounted two cams, E E', the former actuating the admission-valve or stop-cock s' and the latter the exhaust-valve or stop-cock s'', above referred to. The shaft S also carries a belt-pulley, P'', and a grooved pulley, P', the former actuating the magneto-electric generator and the latter the atomizing apparatus. The admission and exhaust valves s' s'' are connected by means of articulated levers A A' to the cams E E', and their extremities carry an anti-friction roller, a a', respectively, that rides in the cam groove or track or over the cam-surface, by which said levers are moved to open or close the admission and exhaust valves. The form of these cams is shown in Fig. 6, and in Fig. 4 I have shown a construction of cam provided with a cam-track. These cams are mounted upon the crank-shaft in such relation to each other that when the piston has reached, or is about to reach the limit of its stroke in one direction the admission-valve is opened and the exhaust-valve closed, and when the said piston has reached or is about to reach the limit of its stroke in a reverse direction the exhaust-valve is opened and the admission-valve closed, as will be readily understood.

Having now described the general construction of my improved engine, it will be understood that any suitable mechanism or appliances may be employed for atomizing or vaporizing the liquid employed to produce the explosive gas and that any suitable means may be employed for igniting the explosive gas within the cylinder-chamber c', to drive the piston in one direction, (the centrifugal force of the fly-wheels carrying the piston in a reverse direction.) I have, however, found, on the one hand, that the small injectors—as in the Hock engine, for instance—for atomizing the liquid or injecting the vapors leave much to be desired, so far as their effectiveness is concerned, the work performed by these devices being imperfect. On the other, the method heretofore resorted to to ignite—i. e., explode—the gases or vapors by means of an electric spark produced from a so-called "Ruhmkorff apparatus," in combination with galvanic elements or Lenoir system, presents, as is well known, great inconveniences, that induced me as early as 1872 to devise means which will be more perfect in their operation, more reliable, more convenient, and simpler in construction, and especially to devise means whereby an electric current may be produced, without the use of a battery, by means of magnetic inductors operated by the engine itself, and I have at last succeeded in obtaining not

only a vaporizer—or, more properly, an atomizer—of great effectiveness and very simple in construction, but also a magneto-electric generator of equally simple construction, of great effectiveness and reliability, which I will now describe in their order.

Referring to Figs. 7, 8, 9, and 10, the latter two figures showing a slight modification in the arrangement of the atomizing-brushes, I 10 is a vessel of suitable construction in communication with a feed-reservoir through pipe i . The relative position between the two is preferably such that the level of the liquid in I will never rise much beyond the center of the 15 shaft S^1 . The latter is mounted in suitable bearings, and carries a brush-wheel, B, to which a continuous rotation in the direction of the arrows, or an intermittent rotation, or an oscillatory movement, may be imparted from the 20 engine mechanism. As shown, the brush-wheel B has a continuous rotation imparted thereto from the pulley P^3 on the crank-shaft S and the pulley P^4 on the brush-wheel shaft S^2 through the medium of a belt or cord. As 25 the brushes b are passing through the liquid they take up a certain quantity thereof and then come in contact with a scraper or shield, I' , whereby any excess of liquid is removed from the brushes b , which afterward come in 30 contact with the adjustable atomizing-plate I'' , where the remaining liquid adhering to the brushes is atomized, and where the compressed air coming from reservoir R through pipe r^2 is 35 mixed with the atomized liquid and carried out of the apparatus through pipe I^2 into the chamber c^1 , and thence, as above described, to the cylinder-chamber c' .

In Figs. 9 and 10 I have shown the atomizing-brush b , mounted on an endless belt, B' , 40 traveling over belt-pulleys P^5 , supported in suitable bearings. Otherwise the operation and construction of the atomizer are the same as those of the one just described.

Instead of causing the brush-belt to travel 45 in a vertical direction, said belt may be caused to travel in a horizontal direction, and the construction and arrangement of these appliances will to some extent depend upon the size of the engine, arrangement of its cylinder, and the 50 space where the engine is located.

Having described the atomizer, I will now 55 describe the magneto-electric generator, referring more particularly to Figs. 11, 12, 13, and 14.

L and L' are two metallic (iron) segments 60 that form the two poles of a powerful magnetic reservoir or magazine, M, which latter is composed of a series of bar-magnets, m m m , &c., and the metallic framing M' , to which said bar-magnets are screwed. The pole-segments L L' are attached to a square plate, M^2 , of a material not influenced by magnetism, and which serves as a support and cover for the same. As shown by Fig. 13, the bar-magnets 65 m are arranged radially upon the pole-segments, and in two groups of an equal number opposite each other. Between the pole-seg-

ments is located the armature-coil O' and its core O, mounted upon a two-part shaft, S^3 S^4 . The core-armature is composed of a metallic core, o , and two metallic disks, o^2 , of soft iron or other suitable magnetic metal. The coil O' is composed of a bobbin, o' , of a suitable insulating substance, mounted on the core o , and upon which is wound the insulated copper wire o^3 , one end of which coil is connected with the metallic part of the apparatus and the other with a sleeve, O^2 , mounted upon the part S^4 of the two-part shaft, and from which it is insulated. The latter part of this shaft 70 has its bearings in the framing M' and a plate, Q, and the part S^3 of said shaft has its bearings in a plate, Q' , and the plate M^2 , said plates Q Q' being secured to the armature O, and serve to connect the shaft therewith. The plate 75 M^2 carries a binding-screw, m^2 , insulated from the plate, but in metallic connection with the sleeve O^2 through the metallic bar m' and the contact-spring s' .

Upon the part S^4 of the shaft, within the 80 framing or supporting-plate M' , is mounted a slotted lever, L^2 , which is actuated or carried along by the pin or stud l' , secured to a belt-pulley, p^2 , mounted upon a short shaft, S^5 , that has its bearings in the metallic framing M' , 85 said shaft having its bearings eccentric to those of shaft S^3 S^4 , and is rotated from the engine through belt-pulley P^2 on main crank-shaft S. By means of this arrangement a differential speed is imparted to the shaft S^4 S^5 and induction-coil. The uniform rotation of the pulleys p^2 P^2 is of great importance, and may be effected in any desired manner and by any of the well-known means. To effect this I have, 90 as shown in Fig. 14, constructed the belt-pulleys P^2 p^2 with peripheral recesses k^2 and the belt B^2 with projections or teeth b^2 , that engage the recesses k^2 , and thus uniformly rotate the pulleys and prevent any slip of belt B^2 .

By the above-described construction and extension of the poles of the magnetic magazine over the entire width of the pole-segments on the one hand, and by the application of the lever movement to rotate the induction-coil on the other hand, the armature is exposed sufficiently long to the magnetic influence of the bar-magnets as to secure a complete and thorough magnetization thereof, while the change in polarity follows very rapidly.

Upon a standard, F', secured to the plate 100 M^2 of the magneto-electric generator, is secured an angular or two-armed lever, U, and upon the part S^3 of the two-part shaft of said generator is mounted a cam, T, upon which rides the extremity of the arm u of lever U, which 105 extremity may be provided with an anti-friction roller, w , for obvious purposes. The arm u^2 of lever U carries a metallic pin, U', that penetrates into the enlarged portion of the exhaust-passage c^6 of the cylinder-chamber c' immediately in front of the stop-cock or valve s^6 . The pin moves gas-tight within the aperture 110 through which it passes, and carries a coiled spring, n^4 , the tension of which tends to force

the lever-arm and pin outward from the passage c^6 . A second pin, U^2 , projects some distance into the passage c^6 , and upon the same plane as the pin U' , the poles of the induction-coil being connected with said pins by wires w^2 w^2 through the binding-screw m^2 and the metallic portion of the generator, as shown in Fig. 14. As plainly shown in Fig. 14, each pin $U' U^2$ terminates in an enlargement or contact-point or button, $u' u^2$, respectively. As the cam T rotates, the arm u^x of lever U is slowly moved inward when the roller w^2 moves up the incline of the cam, and when at its highest point, or greatest distance from the center of the cam, the contact-point u' of pin U' will be in contact with the point u^2 of pin U^2 , and immediately thereafter the extremity of the lever-arm u will drop over the nose t of the cam T , and the contact of the two pins will be interrupted. The sudden interruption of the contact between the points $u' u^2$ produces the spark that ignites and explodes the gas in chamber c' . Thus it will be seen that at each revolution of the cam T the gas is exploded and the piston P moved outward of the cylinder C .

I have described hereinbefore mechanism whereby a differential motion is imparted to the induction-coil and its shaft; and the object 30 of imparting such a movement to the coil and shaft will be apparent, for the reason that it is necessary that the coil during a portion of its rotation should be moved sufficiently slow to insure its thorough magnetization, in order to obtain the necessary current strength to produce the spark, and it should be moved sufficiently fast to break the current as suddenly as possible, in order to produce the spark to ignite and explode the gases; and, as will be readily understood, the cam T will be so mounted upon its shaft as to cause the separation of the contact-pins at the proper time; hence said cam is operated from and timed by the movements of the piston through the piston-driven shaft. 45 The movements of the cam-shaft S^3 , the cam T , and the lever U are so timed relatively to the movements of the piston and gas-inlet valve that when said piston has reached or is about to reach the limit of its inward motion, or after starting on its outward motion, and immediately before or a little after the inlet-valve has been closed, the pins U' and U^2 will be in contact to close the induced electric circuit, and when said inlet-valve is closed the contact 55 will be suddenly broken, as described, thereby producing the electric spark to ignite and explode the explosive gas within chamber c' , and again move the piston outward.

It will be understood that, instead of using 60 a vertical cylinder, the engine may be constructed for use with an inclined or horizontal cylinder, the latter construction being shown in Figs. 4 and 5. The head of the cylinder being removed, it is in all respects the same as 65 the engine hereinbefore described, except as regards such modifications in the construction and arrangement of the parts as are necessary

with the altered position of the cylinder; and, if desired, a separate air-compressor may be employed; or it may be operated without air-compressing mechanism, in which case the outer end of the cylinder may be open; and if, instead of a mixture of a hydrocarburet and atmospheric air, carbureted hydrogen or other explosive gas is used, then the atomizer may be dispensed with, as will be readily understood. 70 As shown in Figs. 4 and 5, the cylinder C is open at one end, the engine being constructed for operation without compressed air. A further modification in the construction of this engine 80 lies in the fact that a cross-head and guide-rods are here dispensed with, which makes the engine more compact. The piston-rod is directly connected with an angular lever or walking-beam, W' , that operates the crank-shaft S through 85 the medium of a connecting-rod, w' . In this construction the inlet and outlet valves or stop-cocks s^5 s^6 are operated by means of two cams, $T^3 T^4$, respectively mounted on the crank-shaft S , and by means of articulated levers $L^3 L^4$, 90 each composed of three lever-arms, $l^3 l^4 l^5$, as plainly shown, the track of the cams $T^3 T^4$ being so formed that at each revolution of the crank-shaft the valves s^5 s^6 are alternately closed and opened, and in such manner that 95 when the admission-valve is open the escape-valve is closed, and vice versa, as will be readily understood.

The operation of the engine is as follows: To start the engine, a partial rotation is imparted to the crank-shaft, whereby the atomizer is set in operation and compressed atmospheric air from the reservoir R admitted to and mixed with the liquid employed to produce the explosive gas, and simultaneously therewith the admission-valve s^5 is opened. The piston P at the same time moves outward, drawing the explosive gas into chamber c' . The magneto-electric generator is also set in motion, and the contact or firing pins $U' U^2$ 100 brought into contact through the medium of the slotted lever L^3 , pin l^2 , and belt-pulleys P^2 p^2 . By the continued rotation of the crank-shaft the admission-valve is closed and the contact between the pins $U' U^2$ suddenly interrupted. The gas admitted is ignited and exploded, which moves the piston outward to the end of its stroke. The air in chamber c is compressed and passes into the receiver R , and the escape-valve is opened to allow the 110 gases to escape from chamber c' , and the piston moves back, drawing air from without through suction-valve V . The power of the piston is transmitted through the cross-head to the connecting-rods $R' R'$, and through them 115 to the crank-shaft S .

I have herein described peculiar and novel constructions and arrangements of atomizing and magneto-electric generating apparatus. I wish it understood that I do not desire to 130 claim these in this application, except in their necessary combination with the engine, as I am about to make separate applications for patents for the same.

Having now described my invention, what I claim is—

1. In a gas-engine, a piston and piston-cylinder constructed to operate as a motor and air-compressor, the admission port and valve of the cylinder, appliances for spraying the liquid from which the explosive compound is derived, appliances for forcing the air compressed by the piston into the sprayed liquid, and an auxiliary valve for forcing air under pressure directly into the admission-port of the cylinder, in combination with a perforated diaphragm located within the admission-port intermediate of the admission-valve and the auxiliary air-valve, and the spraying appliances, substantially as and for the purposes specified.

2. In a gas-engine, a piston-cylinder and piston constructed to operate as an air-compressor, the admission port and valve of the cylinder, appliances for spraying the liquid from which the explosive compound is derived, appliances for admitting the air compressed by the piston in regulated volume to the spraying devices, and suitable valved connections between the two, in combination with an auxiliary valve for admitting air under pressure in regulated volume directly into the admission-port, a perforated diaphragm located in the latter between the admission-valve and the auxiliary air-valve, and spraying appliances and mechanism for operating and timing said admission by the movements of said piston, substantially as described.

3. The cylinder C, provided with suction and check valves in one of its heads and the passage c⁵ in its opposite head, the piston P, connecting-pipe r, and reservoir R, in combination with an atomizer and suitable valve-connection between the latter and the reservoir, the valve s⁵, and the crank-shaft S, all constructed for co-operation as described.

4. The cylinder C, having suction and check valves V V' and a passage, c⁵, in one head, and the passage c⁵ c⁶ in the other head, the pipe r, reservoir R, an atomizer or vaporizer, and suitable valve-connections between the latter and the reservoir, and the valve s⁵ s⁶, in combination with the piston-driven shaft, all constructed for operation as described.

5. The combination of the reservoir R, a vaporizer or atomizer, and a chamber, c⁷, having perforated diaphragm d⁷, with the valved pipes r' r², substantially as and for the purposes specified.

6. In a gas-engine, the combination of a piston and a piston-cylinder constructed to operate as an air-compressor, and a piston-driven shaft, with appliances for atomizing or vaporizing the liquid from which the explosive gas is produced, appliances for delivering the air compressed by the piston to the atomizer, a valve through which the explosive gas is admitted to or excluded from the exploding-chamber of the piston-cylinder, appliances for igniting and exploding the gases admitted to said chamber by the sudden interruption of an induced electric circuit, and an exhaust-valve to exhaust the spent gases from said cylinder, said inlet and exhaust valves and igniting devices being operated from and timed by the movements of the piston through the medium of the piston-driven shaft, substantially as and for the purpose specified.

In testimony whereof I affix my signature in presence of two witnesses.

SIEGFRIED MARCUS.
